(57) CLAIM

The ornamental design for an extendible article holder, substantially as shown and described.

DESCRIPTION

FIG. 1 is a bottom perspective view of the novel extendable article holder in a fully retracted configuration;

FIG. 2 is a bottom perspective view thereof in a partially extended configuration;

FIG. 3 is a top perspective view thereof in said fully retracted configuration;

FIG. 4 is a top perspective view thereof in a partially extended configuration;

FIG. 5 is a bottom perspective view thereof in a fully retracted configuration and depicting a held article such as a lighter in phantom lines;

FIG. 6 is a top plan view thereof in said fully retracted configuration;

FIG. 7 is a bottom plan view thereof in said fully retracted configuration;

FIG. 8 is a first side elevational view thereof in said fully retracted configuration;

FIG. 9 is a second side elevational view thereof in said fully retracted configuration;

FIG. 10 is a first end view thereof; and,

FIG. 11 is a second end view thereof.

The broken line showing of a cigarette lighter in FIG. 5 is for illustrative purposes only and forms no part of the claimed design.

1 Claim, 4 Drawing Sheets
